UNITED STATES PATENT OFFICE.

CONRAD M. GILBERT, OF PHILADELPHIA, PENNSYLVANIA.

DESIGN FOR TRIMMING.

SPECIFICATION forming part of Design No. 13,614, dated February 13, 1883.

Application filed December 18, 1882. Term of patent 7 years.

To all whom it may concern:

Be it known that I, CONRAD M. GILBERT, of Philadelphia, in the county of Philadelphia, and in the State of Pennsylvania, have invented 5 certain new and useful Improvements in Design for Dress and Upholstery Trimming; and I do hereby declare that the following is a full, clear, and exact description thereof, reference being had to the accompanying drawing, making 10 a part of this specification.

In the annexed drawing is shown, in front elevation, a fringe that illustrates my design, which design consists in a heading, A, of any suitable kind, having attached thereto at regular 15 intervals pendants B, which are each longitudinally divided into a carrot-shaped section, b, and one or more balls, b'. Said pendants may be suspended by their carrot-shaped

ends b, or by their ball ends b', or may be alternately reversed, as desired, while in color 20 each may be wholly or in part formed from light or dark shades of material.

Having thus fully set forth the nature of my invention, what I claim as new is—

The design for fringe, consisting of a heading and a series of pendants, each of which pendants is divided longitudinally into a carrot-shaped section and one or more balls, substantially as specified. 25

In testimony that I claim the foregoing I 30 have hereunto set my hand this 2d day of December, 1882.

CONRAD M. GILBERT.
